UNITED STATES PATENT OFFICE.

LEONARD B. BUCHANAN, OF WOBURN, AND FRANKLIN N. CONANT, OF NEWBURYPORT, MASSACHUSETTS, ASSIGNEES TO CHASE-SHAWMUT COMPANY, OF NEWBURYPORT, MASSACHUSETTS, A CORPORATION OF MASSACHUSETTS.

INCLOSED ELECTRIC FUSE.

1,245,187.

Specification of Letters Patent.

Patented Nov. 6, 1917.

Application filed January 8, 1914. Serial No. 811,058.

To all whom it may concern:

Be it known that we, LEONARD B. BUCHANAN and FRANKLIN N. CONANT, citizens of the United States, residing, respectively, 5 at Woburn, in the county of Middlesex, and Newburyport, in the county of Essex, and State of Massachusetts, have invented an Improvement in Inclosed Electric Fuses, of which the following is a specification.

10 In electric fuses having renewable, fusible elements heretofore made, the means employed for detachably connecting the ends of the fusible-elements with the terminals in some instances have been complicated,

15 requiring the services of a skilled workman to make the connections, and in other instances have been simple, but so constructed as to resemble the ordinary forms of binding-posts and other well-known

20 forms of electric connecting-devices, so much so in fact as to suggest and facilitate the use of substitute forms of fusible-elements other than the fusible elements which are adapted to be employed, which are en-

25 tirely unsuited to the requirements of the fuse and involve great danger.

The object of this invention is the provision of an improved form of renewable, fusible-element, and of means for detachably connecting the same to the terminals, both of which are very simple, yet the detachable connecting-means are so constructed that an ordinary piece of fuse-wire cannot be employed as a substitute, and furthermore, they are so entirely unlike the ordinary forms of binding-posts and other well-known electric connecting-devices as not to suggest the use of any other form of fusible-element than that which it is especially designed and intended shall be employed, and are otherwise desirable.

In accordance with this invention the terminals which are usually arranged at the ends of the fuse for engagement or connection with clips or other means to which the circuit-wires are connected, have portions arranged inside the fuse-case which are formed with sockets arranged coaxially with the longitudinal axis of the fuse-case, 45 and said sockets are preferably internally screw-threaded, and the fusible-element, which may be composed of a strip of zinc or some equivalent metal, is provided at

each end with a plug arranged to enter the sockets in the terminals, and in case said 55 sockets are internally screw-threaded said plugs are externally screw-threaded for engagement therewith. Furthermore, in case said sockets are internally screw-threaded the threads are preferably made right and 60 left and the plugs correspondingly threaded. Such a fusible-element, and also such means for detachably connecting it with the terminals may be easily and cheaply manufactured in quantity but do not lend them- 65 selves readily to the employment of substitutes for the fusible-element, as screw-threaded fusible portions of exactly the right size and thread are not readily obtainable. The thread and size should pref- 70 erably be chosen with this object in mind.

Figure 1 is a side elevation and partial longitudinal vertical section of an inclosed electric-fuse embodying this invention.

Fig. 2 is a longitudinal vertical section of 75 the fuse.

Fig. 3 is a side elevation of one form of fusible-element detached from the fuse.

Fig. 4 is an end view of the fuse.

Fig. 5 is a longitudinal vertical section of 80 one of the terminals.

Fig. 6 is a side elevation of one end-portion of the fuse, the end cap or ferrule being represented by dotted lines.

Fig. 7 is an end view of the fuse shown 85 in Fig. 6.

Fig. 8 is a sectional detail view of a modified form of connecting means for the detached fusible element.

10 represents the tubular body of the fuse- 90 case which is here shown as cylindrical in form; 12, 12 are metallic thimbles arranged in the open ends of said body. Each thimble has a circumferential outwardly ex- 95 tended flange 13 at its outer end which abuts against the end of said body, and said flange has notches 14 which are extended there- 100 through longitudinally, two being here shown, which are oppositely disposed, and each notch is arranged opposite one end- portion of a long transverse recess 15 formed in the end of the body, so that the notches, together with their adjacent re- cesses form bayonet-slots. Said thimbles are secured to the body by pins 16. It is 105 an advantage to form the longitudinal slots

in the end-portions of the case in this manner, but the invention is not limited to thus forming them. 20 represents the metallic end-caps or ferrules which are arranged on the ends of the body, and said caps have inwardly extended pins 21, two being here shown, which are oppositely disposed and arranged to enter the bayonet-slots 14, 15, upon a longitudinal and subsequent rotary movement of the caps, thereby to detachably connect the caps with the body. In cases where the fusible-element is made detachable it is desirable that the end-caps also shall be detachable, but the invention is not limited to the precise means here shown for detachably connecting the end-caps with the body. Each end-cap as here shown, has a large center-opening 22 at its end, thereby leaving an inwardly extended marginal lip or flange 23, and at the outer end of each thimble two circular plates 25, 26, are arranged which are coextensive with the end of the body and serve to substantially close said end. The outermost plate 26 is made of metal and has a plurality of holes 27 through it and the innermost plate 25 is made of paper or some equivalent material which extends over and closes said holes 27. Said plates, at the ends of the body, serve to hold the filling which is contained in the body from falling out. The filling may be ground set plaster-of-Paris or asbestos or both, or any other well-known arc-checking substance or substances, but means must be provided at the ends of the body to keep such form of filling from falling out.

The terminals at each end of the fuse-case are made substantially alike and are extended through center holes in the end-plates, and, as here shown, they each comprise an external portion or blade for connection with a pair of spring-clips or other means for establishing a circuit connection, and an internal portion for connection with the fusible-element. The construction of said terminals forms one of the features of this invention, and, as here shown, their external portions 30 are made flat and rectangular in cross-section, forming a blade-like portion, and said blade-like portions are extended through elongated openings 40 in the end-plates 25, 26, and their internal portions 31 are made cylindrical and formed with sockets 32 extended from their ends inward for a considerable depth, said sockets being designed to receive the end-connectors or plugs on the fusible-element, and, as shown in Figs. 2 and 5, said sockets are screw-threaded for the engagement therewith of said plugs, and, in case they are screw-threaded it is preferred that the threads of the two sockets shall be cut, respectively, right and left. Each terminal has holes 33 in its side-walls which are oppositely disposed to admit of a pin 34 being

extended therethrough, and through the adjacent thimbles and side wall of the body of the fuse-case, thereby securely holding the terminal in place. In the manufacture of said terminals they are or may be each composed of a short piece of metal tubing, one end of which is subjected to severe pressure to form the flat blade-like external portion, the remaining portion being left in its original cylindrical form.

The fusible-element which is detachably connected with the terminals and hence may be renewable from time to time, as occasion may require, forms another feature of this invention, and, as here shown, consists of a strip 50 of zinc or other fusible metal which may be selected, having due regard to the requirements of the fuse as to voltage and amperage, and two plugs 51, 51 secured respectively by solder or other means, to its opposite ends. Said strip 50 is of any desired shape and dimensions. Said plugs are designed to enter the sockets 32 in the terminals and preferably are screw-threaded for engagement therewith, and in case said sockets are formed with right and left threads, then said plugs will be correspondingly provided with right and left threads. Said plugs are formed with hexagonal or other shaped heads 52, in order that they may be engaged by a wrench for the purpose of turning the strip, as it will be understood that the strip itself is usually too ductile to withstand any considerable strain, such as may be required to turn it to cause the screw-plugs to tightly engage their sockets.

In case it becomes necessary to renew the fusible-element, the end-caps are removed, together with their associated end-plates and terminals, and the parts reassembled with a new fusible-element. The renewable, fusible-element here shown is simple and may be easily connected with the terminals by a rotary motion of one with respect to the other, and the socketed terminals are very unlike the ordinary binding-posts and other well-known forms of electrical connecting-devices, hence the use of substitute forms of fusible-elements, will not be suggested as convenient.

As a modified form of the invention reference may be had to Fig. 8, wherein the socket 32 in the end-portion of the terminal is made without screw-threads and is slightly tapered, and the plug 51 on the fusible-element is likewise made without screw-threads and is slightly tapered to fit the tapered socket. The tapered portion should be shaped so as not to receive readily a fusible portion not intended for it. A tapering pin 55 is driven through the socketed portion of the terminal and the plug, thereby to detachably connect them together, and in case the plug is made quite long, so as to

extend into the path of the pin 34, its end-portion may be provided with a groove to receive said pin.

I claim:—

- 5 1. An inclosed electric-fuse comprising a fuse-case having removable sheet metal end-caps, terminals arranged at the ends of the case having external flat blade-like portions and internal cylindrical socketed portions,
- 10 10 means for detachably securing said terminals to the fuse-case, and a detachable integral unitary fusible-element composed of the flat metallic fuse-strip and cylindrical plugs secured to its ends which plugs enter the sockets of the terminals and are secured thereto.
- 15 2. An inclosed electric-fuse comprising a fuse-case having removable sheet metal end-caps, terminals arranged at the ends of the case consisting of tubes flattened at one end to form blade-like portions, the other ends of said tubes having cylindrical socketed portions, the former being arranged externally and the latter internally with respect to the case, and a detachable fusible-element having plugs secured to its ends which enter the sockets of the terminals and are secured thereto.
- 20 3. An inclosed electric-fuse comprising a tubular body having transverse recesses in its ends, thimbles arranged in the open ends thereof, each thimble having a circumferential flange abutting against the end of the body, and each flange having notches made shorter than the recesses in the body, and arranged opposite an end-portion of said recesses, thereby to form bayonet-slots, end-caps arranged on the body and inclosing the thimbles and having pins adapted to enter said bayonet-slots, terminals at the ends of the case having blade-like portions projecting through the end caps and engaging portions arranged within the case adapted for engagement with a fusible element, and an integral unitary fusible element arranged within the case and detachably engaging 65 said engaging-portions.
- 25 4. An inclosed electric-fuse comprising a tubular body having transverse recesses in its ends, thimbles arranged in the open ends thereof, each thimble having a circumferential flange abutting against the end of the body, and each flange having notches made shorter than the recesses in the body, and arranged opposite an end-portion of said recesses, thereby to form bayonet-slots, end-caps arranged on the body and inclosing the thimbles and having pins adapted to enter said bayonet-slots, terminals at the ends of the case having blade-like portions projecting through the end caps and engaging portions arranged within the case adapted for engagement with a fusible element, and an integral unitary fusible element arranged within the case and detachably engaging 60 said engaging-portions.
- 30 5. An inclosed electric-fuse comprising a tubular body having transverse recesses in its ends, thimbles arranged in the open ends thereof, each thimble having a circumferential flange abutting against the end of the body, and each flange having notches made shorter than the recesses in the body, and arranged opposite an end-portion of said recesses, thereby to form bayonet-slots, end-caps arranged on the body and inclosing the thimbles and having pins adapted to enter said bayonet-slots, terminals at the ends of the case having blade-like portions projecting through the end caps and engaging portions arranged within the case adapted for engagement with a fusible element, and an integral unitary fusible element arranged within the case and detachably engaging 65 said engaging-portions.
- 35 6. An inclosed electric-fuse comprising a tubular body having transverse recesses in its ends, thimbles arranged in the open ends thereof, each thimble having a circumferential flange abutting against the end of the body, and each flange having notches made shorter than the recesses in the body, and arranged opposite an end-portion of said recesses, thereby to form bayonet-slots, end-caps arranged on the body and inclosing the thimbles and having pins adapted to enter said bayonet-slots, terminals at the ends of the case having blade-like portions projecting through the end caps and engaging portions arranged within the case adapted for engagement with a fusible element, and an integral unitary fusible element arranged within the case and detachably engaging 60 said engaging-portions.

In testimony whereof, we have signed our names to this specification, in the presence of two subscribing witnesses.
